DESIGN FOR AN OIL STOVE OR ANALOGOUS ARTICLE

Eugene A. Lindemann, Milwaukee, Wis., assignor to A. J. Lindemann & Hoverson Company,
Milwaukee, Wis., a corporation of Wisconsin

Application April 30, 1937, Serial No. 68,880

Term of patent 14 years

To all whom it may concern:

Be it known that I, Eugene A. Lindemann, a citizen of the United States, residing in the city of Milwaukee, county of Milwaukee, and State of Wisconsin, have invented a new, original, and ornamental Design for an Oil Stove or Analogous Article, of which the following is a specification, reference being had to the accompanying drawing, forming a part hereof.

The figure is a perspective view of an oil stove or analogous article showing my design. The sides of the oil burner not shown are substantially plain.

I claim:

The ornamental design for an oil stove or analogous article substantially as shown and described.

EUGENE A. LINDEMANN.
